UNITED STATES PATENT OFFICE.

HENRY H. BLAKE, OF PITTSBURG, PENNSYLVANIA, ASSIGNOR TO HIMSELF
AND THOMAS A. NOBLE.

AUTOMATIC FOLDING CHAIR.

SPECIFICATION forming part of Letters Patent No. 400,183, dated March 26, 1889.

Application filed February 17, 1887. Serial No. 227,994. (No model.)

To all whom it may concern:

Be it known that I, HENRY H. BLAKE, a citizen of the United States, and a resident of Pittsburg, county of Allegheny, and State of Pennsylvania, have invented a certain new and useful Improvement in Automatically-Folding Chairs; and I do hereby declare the following to be a full, clear, and exact description thereof, reference being had to the accompanying drawings, in which—

Figure 1 indicates a perspective view of my improved automatically-folding chair having its seat not forced down but resting upon its seat-springs. Fig. 2 indicates a detached sectional view of the seat and side of the chair. The dotted lines indicate the position of the seat, &c., when the former is relieved from pressure and thrown by the automatic action of the seat-springs toward the back of the chair. Fig. 3 indicates a side elevation of chair, partly in section, showing the inner side of the opposite side of same, the forward part of the side in which the seat is supported being broken away to show the springs C and c.

The object of my invention is to produce an automatically-folding chair adapted especially for theaters and public halls. To this end I propose to construct opera or theater chairs in such manner that when pressure is applied to the seat forcing the latter down into position its seat-springs are deflected with sufficient force to throw or swing the seat toward the back of the chair at the moment the weight is removed.

In the drawings, A indicates the body of the chair, which may be constructed in ordinary or suitable manner, and is provided with an ordinary seat, A', which is securely attached to a transverse cross-bar, B. This cross-bar B is provided with triangular-shaped ends, which project into perforations or apertures in the upper portion of the seat-supports and rest upon a metallic spring, C, which is attached rigidly at its rear end to the rear portion of each side of the chair. c indicates a small auxiliary spring attached to each side of the chair, and projecting at its forward end downward into and toward the front portion of the apertures in the upper portion of the

seat-supports in which the triangular ends of the cross-bar B engage.

The operation of the device is as follows: The seat being tilted forward is caused by its own weight to lie in the position shown in Fig. 1, the triangular ends of the cross-bars resting on the free ends of the lower springs. At the moment the weight of the occupant forces the seat downward the triangular ends of the cross-bar pass below the downwardly-projecting ends of the auxiliary springs and force the springs C down until the ends of the cross-bar rest on the bottom of the apertures into which they enter. As soon as the weight is removed, the springs C throw the cross-bar upward and the inner side of its ends come suddenly into contact with the downwardly-projecting ends of the auxiliary springs. This imparts a tilting action to the bar turning it, so that the seat swings back toward the rear of the chair.

It is obvious that the auxiliary springs may be dispensed with as the same result can be secured by forming shoulders in the rear upper portions of the apertures to engage the inner sides of the triangular ends and tilt the bar when the latter is thrown up by the action of the seat-springs. It is also obvious that in lieu of the seat-springs the chair might be provided with an air or water compressing apparatus adapted to compress air or water through the force derived from the weight of the chair occupant, and to throw the seat backward by means of force derived from such pressure at the instant the use of the seat is discontinued. Some of the advantages of my invention are, first, simplicity of construction and economy of manufacture; second, it has few parts, is durable, and not likely to get out of order, and, third, as the cross-bar is arranged back of the center of the seat the latter can be tilted forward, and is caused to remain by its own weight almost down to the position of use, differing materially in this respect from other spring-seats, which require the expenditures of considerable force to pull them down into position and must be held down until sat upon.

Having described my invention, what I

claim, and desire to secure by Letters Patent, is—

In an automatic folding chair, the combination of a seat supported by and adapted to swing backwardly upon a cross-bar having triangularly-shaped ends loosely pivoted in slots or bearings in the forward upper part of the arms or sides of the same, springs secured within the arms or sides of the same, adapted when extended to support the ends of the cross-bar in the upper part of the slots or bearings and when compressed to sink toward the bottom of the same, and springs attached to the

arms or sides of the chair at the upper rear end of the slots or openings, and projecting downwardly and terminating near the bottom thereof, adapted to engage the acute edges of the triangularly-shaped ends of the cross-bar when said bar is thrown upward, whereby the seat is tilted or thrown vertically toward the back of the chair, substantially as and for the purpose herein described.

HENRY H. BLAKE.
